UNITED STATES PATENT OFFICE.

FREDERICK A. SCHOSOW, OF DETROIT, MICHIGAN.

FLUSHING VALVE.

Application filed May 25, 1925. Serial No. 32,635.

To all whom it may concern:

Be it known that I, FREDERICK A. SCHOSOW, citizen of the United States, residing at Detroit, county of Wayne, State of Michigan, have invented a certain new and useful Improvement in Flushing Valves, and declare the following to be a full, clear, and exact description of the same, such as will enable others skilled in the art to which it pertains to make and use the same, reference being had to the accompanying drawings, which form a part of this specification.

My invention relates to a valve for flushing closet bowls or for other like purposes and is designed more particularly for use in combination with a pressure tank so designed that the water delivered to the tank from a water supply system under pressure compresses the air within the tank—the compressed air afterwards subsequently serving as a medium for expelling the water from the tank with sufficient force to maintain a siphon in the closet bowl for a predetermined period of time.

25 Flushing valves have been used in connection with pressure tanks in the manner indicated but so far as known these valves are designed so that they begin to close immediately following their manual operation, the valve closing entirely under full pressure in a limited length of time, thereby necessitating the employment of a tank adapted to receive much more water than is actually used at each flush in order that 30 pressure may not be greatly diminished during the flushing period, otherwise the valve must be adjusted for a specific pressure which if not maintained will result in the valve remaining open indefinitely.

40 The primary object, therefore, of the present invention is to construct a valve adapted to remain open as long as the volume of water is sufficient to maintain the siphon in the closet bowl and the volume of 45 water delivered to the bowl is by this means determined by the size of the pressure tank which is therefore preferably just large enough to maintain sufficient water to properly flush the bowl. Such an arrangement 50 results in a more economical use of water and a longer or shorter flush may be obtained by varying the size of the pressure tank instead of by regulating the flushing valve. However another available method

of varying the length of a flush is by regulating the velocity of the water supply entering the tank during the flushing period, thereby regulating the speed at which the pressure within the tank diminishes to accord with the delivery of water to the bowl.

55 Another feature of the invention resides in the fact that the valve will not close until the rate of flow appreciably diminishes, there being no limit to the volume of water that the valve will deliver, therefore it may be used if desired to empty a tank containing one hundred or more gallons of water as effectively as one containing four or five gallons, commonly employed to flush the 60 usual types of closet bowls.

65 Another object of the invention is to provide for a comparatively slow opening of the valve, thus eliminating the gushing noise ordinarily occurring when a full force of water is employed to drive the air quickly 70 out of the water passages within the closet bowl.

75 Another object of the invention is to provide against the valve closing until the volume and pressure have been reduced to a very small fraction of the initial pressure, thereby avoiding the hissing noise which 80 commonly occurs when a valve is closing under full volume and pressure.

85 Another object of the invention is to control the final closure of the valve so as to admit a copious amount of water at a slow rate of flow—the water remaining in the 90 bowl as a seal against sewer gases or other odors.

95 Another object of the invention is to provide means insuring the slow opening and slow closing of the valve which is entirely independent of the means provided to maintain the valve in its open position.

100 Another feature of the invention is that the means controlling the slow opening and slow closing of the valve is thoroughly cleansed at each manipulation of the manually operated means for actuating the valve.

105 With the foregoing and other objects in view which will appear as the description proceeds the invention further resides in the combination and arrangement of parts and in the details of construction hereinafter described and claimed it being understood that changes may be made in the precise embodiment of the invention herein dis-

closed without departing from the spirit of the same.

In the drawings accompanying this specification:

5 Figure 1 is a diagrammatic view partly in perspective and partly in section showing a pressure tank and suitable piping leading from a water system—not indicated—to a pressure tank that the delivery of water thereto may compress the air in the tank that the water contained in its closed chamber may be subsequently delivered through a pipe leading to a closet bowl—the delivery of water through said last named pipe being controlled by a manually operated valve forming the subject matter of this invention.

10 Figure 2 is a vertical cross-sectional view through the flushing valve showing it in its normal position whereby the water contained in the pressure tank is held against release.

15 Figure 3 is a similar sectional view through the valve showing the handle by which it is manually operated in an inclined position to actuate a bell-crank lever, whereby a pin resting upon one of its arms is raised to force a releasing valve from its seat.

20 Figure 4 is a similar sectional view with certain parts broken away and in elevation—in which in addition to the releasing valve, the main valve is also raised—while the manually operated lever is shown released from manual control and returned to its normal horizontal position through the action of a spring—indicated in the preceding figures—the releasing valve however is held off its seat together with the main valve by the pressure of water flowing from the pressure tank through the valve to the closet bowl, as indicated by the arrows.

25 Figure 5 is a like cross-sectional view showing the releasing valve seated—the main valve being "open" and the pressure of water entering the chambered body from the pressure tank now tends to force the main valve to its seat, as shown in Figure 2—the closing movement being relatively slow.

30 Figure 6 is a plan view of the valve with parts broken away.

35 Figure 7 is a horizontal cross-sectional view with parts broken away, taken on or about line 7—7 of Figure 3.

40 Figure 8 is a fragmentary horizontal cross-sectional view taken on or about line 8—8 of Figure 4.

45 Figure 9 is a horizontal cross-sectional view with parts broken away taken on or about line 9—9 of Figure 4.

50 Figure 10 is a perspective view of the wing guide.

55 Referring now to the letters of reference

placed upon the drawings in which like reference characters designate the same parts in the several views:

The valve body A, is connected by suitable piping X, to a pressure tank Z, into which water from a water supply system—not shown—flows through the piping Y, compressing the air in the tank in accordance with the pressure of the water delivered to the latter.

75 A cap cover A¹, is bolted to an annular flange a projecting outwardly from the upper end of the valve body—between which is secured a diaphragm B, preferably formed of leather, which serves also as a washer 80 between the cap-cover and the body of the valve: This diaphragm together with all the working parts connected with the main valve—hereinafter more particularly described—may be removed as a unit from the valve 85 body for inspection or repairs.

90 The main valve D, includes a wing guide E, having a limited vertical movement in a horizontal partition d between the water inlet and the discharge outlet of the valve body. Projecting upwardly from the partition is an annular rim surrounding the bore forming the seat A^a of the main valve.

95 Mounted centrally upon a shoulder in an annular screw-threaded extension of the wing guide is an annular washer F which closes against the seat of the main valve—said washer being secured by a flanged nut G, screwed upon the annular upwardly extending screw-threaded end of the wing 100 guide.

105 The washer F is further secured by a collar H having a flange overlapping the outer edge of the washer. The collar H is screwed upon the flanged nut G and also to an annular inverted cup-shaped member I having an annular neck projecting through the diaphragm B where the latter is engaged by a beveled-edge washer C screwed upon the upwardly projecting annular neck I^a of the 110 cup-shaped element.

115 C^a denotes a flanged nut screwed upon the neck I^a, overlapping and bearing against the tapering washer C to hold the diaphragm firmly against a shoulder formed by the wall of the inverted cup I, chamfered at the upper outer edge.

120 Screwed upon an annular stem of the nut C^a is a cap J having both central and transverse connecting orifices through its wall—the cap J is milled to facilitate ready removal or replacement upon the end of the nut C^a.

125 Loosely sleeved in a vertical bore in the wing guide E—which serves to maintain the main valve centrally within the valve chamber—is a loose fitting pin K, having end portions of relatively smaller diameter to provide a shoulder K¹, which upon contacting with a shoulder in the bore of the wing 130

guide prevents the pin from dropping out of the latter. The pin K operates as a contacting means to connect a manually operated bell-crank lever L with a releasing valve M, which is adapted to seat against an annular washer E^a fitted in the lower end of the upwardly projecting annular extension E^b, of the wing guide and which is held in place by an elongated collar E^c, having a knurled head to facilitate its ready removal or adjustment.

5 The releasing valve M is tapered at its lower end and seats against the wall of the washer E^a, to normally close the opening 10 through the latter.

Extending upwardly from the tapered end of the releasing valve M is a tubular portion M^a having a plurality of holes m adjacent its lower end—the tubular portion 20 M^a at its upper end is provided with a flat disc M^b of relatively large diameter which is adapted to seat at its outer marginal edge against a shoulder I^c formed in the bowl of the inverted cup-shaped element—there being a space I^d above the disc to allow egress of water through the releasing valve—when in its open or raised position with the disc of the valve against the shoulder I^c of the inverted cup-shaped element.

30 Sleeved within the tubular portion of the releasing valve is a coiled spring N bearing at its lower end against the wall of the tapering valve and at its upper end against the overlapping flange of the nut C^a, screwed 35 upon the tubular neck of the inverted cup-shaped element.

Between the cap J and the counterbored annular neck of the nut C^a is placed a disc P, through which is drilled a relatively small hole—the size of which determines the speed at which the valve may open and close—water being expelled through the hole during the opening phase and is again admitted during the closing phase of movement of the main valve.

45 While the main valve is closing water passes through the aperture in the disc comparatively slowly, while on the contrary when the valve is opening the water pressure 50 against the lower surface of the diaphragm forces the water through the aperture in the disc with comparative rapidity—thus any foreign matter that may have become lodged around the disc is washed down and out.

55 The aperture in the disc is further cleaned at each flush by means of a wire stem Q—preferably of gold—which passes through the disc aperture and projects from the upper end of a rod Q^a, slidable within 60 a tube R, sleeved within the coiled spring N, the upper end of the tube being flanged to overlap the counterbored wall of the annular stem of the nut C^a—the lower end of the tube being flanged inwardly to engage a flattened portion Q^b of the rod to prevent

the latter dropping through the tube when removing the parts for inspection or repairs. The rod Q^a is loosely fitted in the lower end of the tube and projects through the latter and rests upon the releasing valve that it 70 may be raised when the valve is lifted by the manual operation of the bell-crank lever.

It will now be apparent that each time the releasing valve is manually operated the wire Q is moved upwardly through the aperture in the regulating disc, thereby removing any foreign particles which may have found temporary lodgment at this point.

80 The disc is preferably made of non-corrodible metal or other material, reducing to the minimum the possibility of the aperture becoming clogged—the pin providing a facile means for cleaning the aperture in the disc without taking the valve apart.

85 Attention is again directed to the beveled edge washer C screwed upon the neck I^a of the inverted cup-shaped element, so constructed that when pressure is exerted against the lower face of the diaphragm B, the diaphragm is forced against its beveled portion, thereby transferring the pressure to the washer and receiving the strain upon the diaphragm.

90 In Figures 2 and 3 is shown the construction of the manually operated "universally actuated" handle W for actuating the bell-crank lever L, whereby the releasing valve is operated.

95 The end of the handle W projects through a contracted opening in the end of the collar S, screwed into a lateral extension of the valve body and is fitted with an arc-shaped end W^a adapted to bear against a spring actuated plunger T, supported centrally within the collar by a plug T^a, having a flange projecting between the end of the collar S and a shoulder in the wall of the valve body.

100 V denotes a rubber gasket or washer overlapping the end of the plug T, its marginal edge extending between the plug and valve body and is secured to the plunger by a milled screw V^a, which in turn bears against one of the arms of the bell-crank lever, 105 whereby the latter may be actuated upon operating the handle.

110 Having indicated the several parts by reference letters the construction and operation of the device will be readily understood:

115 The valve having been connected with the pressure tank Z—which may be either at the same altitude as the valve or higher or lower as desired, the pressure tank being in turn connected with the source of water supply—water is admitted to the tank from said source of supply.

120 The incoming water compresses the air within the tank until it equals the pressure

under which the water is delivered to the tank.

The valve during this period is normally closed except that it may be operated several times to expel air from the connecting pipes and chamber in the valve body above the diaphragm. The operation thereafter is as follows:

Manipulation of the manually operated handle *W* actuates the bell-crank lever *L* which in turn pushes the loose fitting pin *K* upwardly in the bore of the wing-guide *E* until it impinges upon the lower end of the releasing valve *M*, forcing the latter from its seat, the disc *M^b* being forced upwardly by the valve against the shoulder *I^c* of the cup-shaped element *I*—a unitary part of the main valve.

Attention is now called to the relatively small opening *i* between the collar *H* and the inverted cup-shaped element *I*, of the main valve—through which and the ports *i¹*, the full pressure of water may pass to the lower face of the releasing valve *D*. It also circulates through the space *h*, between the outer diameter of the collar *H* and the valve body, so that the water pressure may pass to the lower face of the diaphragm. This water pressure holds the release valve in its raised position—whereupon the water above the diaphragm of the main valve passes down and outwardly through the aperture in the regulating disc—thereupon the main valve slowly opens.

The full flush however cannot be attained until the collar at the top of the wing guide has been raised above the opening through the main valve seat. During this interval a relatively small amount of water passes through the grooves *e* of the collar of the wing-guide which serves the purpose of gradually expelling the air that is normally in the water passage of the closet bowl, thereby eliminating the gurgling or gushing noises that ensue when ample water to create a full flush is admitted instantaneously to the bowl.

As the valve continues to rise the volume of water passing through the valve increases until sufficient to create and maintain siphonage of the bowl—the valve remaining in full open position as long as the volume is ample to maintain siphonage. The length of time during which the bowl will continue to siphon is dependent upon the size of the pressure tank employed, plus the volume of supply that is added to that in the pressure or storage tank while the valve is open.

When the pressure tank is empty, or nearly so, the volume necessarily is greatly decreased and the pressure of water entering the main valve becomes insufficient to maintain the releasing valve in its open position.

The releasing valve, therefore, is forced to its seat by the coiled spring within the main

valve. The force of gravity plus the small remaining water pressure combine at this point to seat the main valve and the water flowing through the small opening provided between the collar and the inverted cup-shaped element of the main valve passes upward and through the aperture in the disc of the releasing valve.

This closing movement however is comparatively slow and until the main valve is entirely closed water flows past the collar to the top of the wing guide. The volume of water that passes however is much too small to maintain a siphon and therefore it remains in the bowl forming a copious seal against sewer gases.

Owing to the fact that the water pressure is now small, the final closure of the main valve is practically noiseless in contrast to the whistling or hissing noises inevitable with valves of this type which close under, or nearly, full primary pressure.

Valves of this type designed to close under full water pressure usually waste considerable water before finally closing as the pressure is considerably diminished after the valve is fully open rendering them inapplicable for use with a pressure tank unless the tank is large enough so that a single flush only slightly diminishes the pressure in the tank.

The present valve is constructed primarily for use with a comparatively small pressure tank which together with a certain quantity of supply water entering the tank while emptying provides the exact quantity of water required for each flush, and due to its slow opening and closing while the water pressure is practically nil a quietness of operation is attained which is not secured by other valves of this type.

Having thus described my invention what I claim is:

1. In a device of the character described; a valve body having inlet and discharge ports; a normally closed main valve adapted to govern the flow of water through the valve body; means for actuating the valve, and means including a releasing valve controlled by water passing through said valve body at a predetermined volume and pressure for supporting said main valve in open position until the volume and pressure of water in the valve body is insufficient to maintain the valve longer in open position.

2. In a device of the character described; a valve body having ports for the admission and discharge of fluids; a normally closed main valve for controlling the flow of the fluid; means for actuating the main valve; and means including a releasing valve adapted to automatically maintain the main valve in open position during any period of time in which the rate of flow through the main valve is sufficient to maintain a pre-

determined pressure and volume within the valve.

3. In a device of the character described; a valve body having ports for the admission and discharge of water; a normally closed main valve for controlling the flow of the water; means for actuating the main valve; means including a releasing valve for maintaining the main valve in open position during the period of time in which the rate of flow through the valve is sufficient to maintain a predetermined pressure and volume within the valve; and means adapted to automatically close the main valve when the rate of flow through the valve body is insufficient to maintain said valve in open position.

4. In a device of the character described; a valve body having ports for the admission and discharge of liquids; a normally closed main valve adapted to control the flow of liquid through the body; a normally closed releasing valve adapted when actuated to cause the operation of the main valve due to the passage and pressure of the fluid controlled thereby; and means for maintaining the releasing valve automatically in an open position during any period of time the rate of flow through the valve is sufficient to maintain a predetermined pressure and volume within the valve body.

5. In a device of the character described; a valve body having ports for the admission and delivery of liquids; a normally closed main valve adapted to control the flow of liquid through the body; a normally closed releasing valve adapted when actuated to cause the operation of the main valve due to the passage and pressure of the fluid controlled thereby; means for automatically maintaining the releasing valve in an open position during any period of time the rate of flow through the valve is sufficient to maintain a predetermined pressure and volume within the valve body; and means adapted to automatically close the main valve whenever the rate of flow through the valve body is insufficient to maintain said valves in open position.

6. In a device of the character described; a valve body having ports for the admission and delivery of liquids; a normally closed main valve adapted to control the flow of liquid through the body; a normally closed releasing valve adapted when actuated to cause the operation of the main valve due to the passage and pressure of the fluid controlled thereby; means for automatically maintaining the releasing valve in an open position during any period of time the rate of flow through the valve is sufficient to maintain a predetermined pressure and volume within the valve body; means adapted to automatically close the main valve whenever the rate of flow through the valve body

is insufficient to maintain said valves in open position; and means for actuating the releasing valve.

7. In a device of the character described; a valve body having ports for the admission and delivery of liquids; a normally closed main valve adapted to control the flow of liquid through the body; a normally closed releasing valve adapted when actuated to cause the operation of the main valve due to the passage and pressure of the fluid controlled thereby; means for automatically maintaining the releasing valve in an open position during any period of time the rate of flow through the valve is sufficient to maintain a predetermined pressure and volume within the valve body; means adapted to automatically close the main valve whenever the rate of flow through the valve body is insufficient to maintain said valve in "open" position; and means for manually actuating the releasing valve.

8. In a device of the character described; a valve body having ports for the admission and delivery of liquids; a normally closed main valve adapted to control the flow of liquid through the body; a normally closed releasing valve adapted when actuated to cause the operation of the main valve due to the passage and pressure of the fluid controlled thereby; means for automatically maintaining the releasing valve in an open position during any period of time the rate of flow through the valve is sufficient to maintain a predetermined pressure and volume within the valve body; means adapted to automatically close the main valve whenever the rate of flow through the valve body is insufficient to maintain said valves in open position; means for manually actuating the releasing valve; and means for automatically limiting the rate of movement of the main valve from closed to open position.

9. In a device of the character described; a valve body having inlet and outlet ports; a normally closed main valve for controlling the flow through said body; means for automatically maintaining the releasing valve in open position during any period of time in which the rate of flow through the valve is sufficient to maintain a predetermined pressure and volume within the valve; and means for limiting the rate of movement of the main valve from open to closed position, operative only when the rate of flow through the main valve ports is of insufficient volume to automatically maintain the main valve in open position.

10. In a device of the character described; a valve body having ports for the admission and discharge of water; a normally closed main valve for controlling the flow of water; means for actuating the main valve; automatically operated means for maintaining the releasing valve in an open position dur-

- ing the period of time which the rate of flow through the valve is sufficient to maintain a predetermined pressure and volume within the valve; means adapted to automatically close the main valve when the rate of flow through the valve body is insufficient to maintain said valve in open position; and unitary means for limiting the rate of movement of the main valve from the closed position to the open position and from the open toward the closed position.
11. In a device of the character described; a valve body having ports for the admission and discharge of water; a normally closed main valve for controlling the flow of water; means for actuating the main valve; automatically operated means for maintaining the releasing valve in open position during the period of time in which the rate of flow through the valve body is sufficient to maintain a predetermined pressure and volume within the valve; means adapted to automatically close the main valve when the rate of flow through the valve body is insufficient to maintain said valve in open position; means for gradually augmenting the initial flow of water until a maximum flow is reached; and means for diminishing the maximum flow to a lesser flow of a predetermined quantity and volume prior to the main valve returning to its closed position.
12. In a device of the character described; a valve body having water inlet and outlet ports; a normally closed main valve; a normally closed releasing valve, whereby the main valve is actuated; means for limiting the rate of flow into and from a water chamber in said valve body, whereby the opening and closing of the main valve may be controlled; and means for maintaining the releasing valve in an open position during any period of time that the rate of flow through the main valve ports exceeds a predetermined volume.
13. In a device of the character described; a valve body having water inlet and outlet ports; a normally closed main valve; a normally closed releasing valve, whereby the main valve is actuated; means for limiting the rate of flow into and from a water chamber in said valve body, whereby the opening and closing of the main valve may be controlled; means for maintaining the releasing valve in an open position during any period of time that the rate of flow through the main valve ports exceeds a predetermined volume; and means for actuating the releasing valve.
14. In a device of the character described; a valve body having inlet and outlet ports; a main valve; a releasing valve; means for maintaining the releasing valve in an open position controlled by a predetermined minimum water pressure; means for automatically closing the releasing valve when the water pressure is less than the predetermined amount.
15. In a device of the character described; a valve body having inlet and outlet ports; a main valve; a releasing valve; means for maintaining the releasing valve in an open position controlled by a predetermined minimum water pressure, means for automatically closing the releasing valve when the water pressure is less than the predetermined amount; and means for actuating the releasing valve.
16. In a device of the character described; a valve body having inlet and outlet ports; a main valve; a releasing valve; a diaphragm attached to the main valve dividing the valve body into two chambers; an annular element extending from the main valve through the diaphragm connecting the upper and lower chambers of the main valve for the passage of water; a perforated disc carried by the annular element; means including a wire movable through the perforated disc adapted to be actuated by the releasing valve; and means for raising the releasing valve.
17. In a device of the character described; a valve body having inlet and outlet ports; a main valve slidable in the valve body; a diaphragm attached to the main valve dividing the valve body into upper and lower chambers; a releasing valve having an enlarged disc at its upper end adapted upon raising the releasing valve to close a passage normally open through the diaphragm; said releasing valve being maintained in its raised position by the water pressure against the underside of said disc until the water pressure falls below a predetermined rate.
18. In a device of the character described; a valve body having inlet and outlet ports; a main valve having a wing guide slidable in a central bore through a partition having an annular rim forming a seat for the valve; a diaphragm attached to the main valve dividing the valve body into upper and lower chambers; said main valve having an annular neck extending through the diaphragm into the upper chamber; a nut screwed on said neck having a central bore; a cap screwed on the neck of the nut having central and transverse connecting bores; a perforated disc lodged between the nut and cap; a releasing valve having an enlarged disc at its upper end adapted when raised to close a passage normally open through the diaphragm; means fitted with a wire movable through the perforated disc actuated synchronously with the operation of the releasing valve, and means for raising the releasing valve.
19. In a device of the character described; a valve body having inlet and outlet ports; a main valve having a wing guide slidable

in the valve body; a diaphragm attached to the main valve dividing the valve chamber into two parts; a releasing valve adapted when seated to close a port through the wing 5 guide; said releasing valve having an enlarged disc connected therewith by a tubular neck adapted upon raising the releasing valve to an open position to close a passage 10 normally open for the passage of water into the upper main valve chamber; said disc valve being adapted to be supported in its upper position by the water pressure against the lower side of the disc until said pressure is diminished below a predetermined volume.

15 20. In a device of the character described; a valve body having inlet and discharge ports; a main valve controlling the passage of water through the valve body; a diaphragm secured to the main valve dividing 20 said valve body into upper and lower chambers; a manually operated releasing valve having a disc within the body of the main valve, adapted when actuated to release water above the diaphragm, whereby the 25 main valve may be raised by water pressure below the diaphragm; and a spring adapted to seat the releasing valve when water pressure acting against the underside of its disc falls below a predetermined pressure.

30 21. In a device of the character described; a valve body having inlet and discharge ports; a main valve having a wing guide; a diaphragm secured to the main valve dividing said valve body into upper and lower 35 chambers; a manually operated releasing valve having a disc, located within the body of the main valve; a movable plunger loosely sleeved within the wing guide adapted to act upon the releasing valve; a bell crank lever; a manually operated handle adapted when tilted to rock the bell crank lever and thereby actuate the plunger to raise the releasing valve; and a spring for returning the handle when released from manual control to its 40 normal position.

45 22. In a device of the character described; a valve body; a main valve controlling the

passage of water through the valve body comprising a wing-guide, slidable through a central bore in the valve body and surrounded by an upstanding flange forming the valve seat; an annular disc mounted on an upstanding collar integral with the wing guide; a nut screwed on the collar adapted to bear against the disc; an inverted cup-shaped element having a plurality of ports through its side wall and a central annular neck; a flanged collar screwed to the cup-shaped element and overlapping the annular disc having ports connecting with the ports 60 of the cup-shaped element; a diaphragm adapted to divide the valve body into upper and lower chambers with a central opening to receive the neck of the cup-shaped element; a washer screwed to the neck of the cup-shaped element having a beveled edge to receive the thrust of the diaphragm; a flanged nut having an annular neck screwed to the neck of the cup-shaped element; a tube extending through the neck of the cup-shaped element supported by the flanged nut; a perforated disc mounted on the end of the tube; a cap nut having central and transverse bores screwed to the neck of the flanged nut to retain the disc in position; 70 a releasing valve and a relatively large disc joined together by a tubular neck, adapted to close a passage normally open into the upper chamber, whereby the main valve may be operated; a rod located within the tube 75 having an upstanding pin slidable through the perforated disc actuated through the operation of the releasing valve; a spring supported in the tubular neck of the releasing valve adapted to return the latter to 80 its seat; a loose fitting plunger rod lodged in a bore extending through the wing-guide of the main valve, adapted when actuated to raise the releasing valve; and means for 85 manually actuating said plunger rod.

In testimony whereof, I sign this specification.

FREDERICK A. SCHLOSSOW.
